POWDER DISPENSING DEVICE

Edgar L. Zehrbach, Mansfield, Ohio, assignor to Westinghouse Electric Corporation, East Pittsburgh, Pa., a corporation of Pennsylvania

Filed Mar. 14, 1962, Ser. No. 179,814

1 Claim. (Cl. 222—70)

This invention relates to a powder dispensing device, especially for dispensing a powder which has pronounced bridging characteristics, such as diatomaceous earth and particularly a product thereof known as "Diatomite" which is extensively used in dry cleaning machines, and has for an object the provision of a dispensing device which will accurately dispense measured quantities of such powder without clogging up in spite of the bridging tendency of the powder. The term "bridging" is understood to mean the tendency of a powder to build up in an arch over a void. This is a kind of self-packing effect which is characteristic of certain materials.

Diatomite is one of the best known filtering agents for entrapping mechanical particles and is extensively used in dry cleaning machines for removing soiling substances from the dry cleaning fluid. It is usual to keep a dry cleaning machine in operation for a number of batches of materials or goods (usually clothing) between changes of dry cleaning fluid; and the cleaning fluid is kept in circulation at all times, even between batch cleanings.

It has been found that best results with the use of a minimum amount of filter powder are produced by introducing an initial quantity or batch of powder when fresh cleaning fluid is put into the machine and thereafter adding an additional quantity or batch of powder for each batch cleaning operation until fresh cleaning fluid is again added.

Dispensers for adding batches or charges of filter powder have been provided for dry cleaning machines but they have been unsatisfactory because they did not dispense accurate quantities or because they clogged up due to the bridging effect and stopped supplying powder altogether.

The device provided by the present invention has been developed for use with dry cleaning machines and has been found to give excellent performance in this service, hence will be disclosed in connection with this particular use but with the understanding that it has other uses.

The invention also provides means for assuring that the dispensing openings will never be left in registry when the operation is stopped, whereby to avoid the flow of materials except when wanted.

The objects of the invention as well as certain novel features and advantages will be apparent from the following description of an exemplary embodiment thereof, reference being made to the accompanying drawings, wherein:

FIG. 1 is a side elevation, partly cut away, of a dry cleaning machine installation having a filter powder dispenser embodying the invention;

FIG. 2 is an enlarged shortened vertical section and elevation of the dispenser;

FIG. 3 is a transverse section taken on the line 3—3 of FIG. 2;

FIG. 4 is an isometric view of a dispenser plate alone; and

FIG. 5 is a reduced section taken on the line 5—5 of FIG. 2 showing a cam and switch mechanism for controlling the stopping point of the dispenser.

As shown in FIG. 1, a dry cleaning machine 10 has a tub 11 with a filling door 12 providing access to a rotating goods-holding basket 13 located within the tub. Cleaning fluid is continuously circulated by a suitable pump from the bottom of the tub by way of an outlet

2

pipe 15 through a filter unit 16 and back into the tub by way of a return pipe 17. The filter unit as well as dry cleaning machines of this type are well known in the art and need no further description.

5 A filter powder dispenser 20 forming the subject of the present invention is secured to the top of the tub and delivers batches of powder in charges into the tub by way of an inlet tube 21. For present purposes it is necessary only to know that the powder gets into the liquid in the

10 tub and is conveyed by the liquid to the filter unit 16.

The dispenser 20 includes a container, preferably barrel-shaped, comprising a bottom 22 and a side or cylindrical wall 24. It is to be particularly noted that the bottom 22 is inclined at an angle to the horizontal. This is preferably effected by inclining the entire container, thereby utilizing a container having its axis or center line disposed at right angles to the plane of the bottom, both being inclined at the same angle relative to the vertical and horizontal, respectively. In its lowermost portion, 15 or adjacent its lower edge, the bottom 22 is provided with a discharge opening 23, which is preferably of a truncated sector shape, as shown in FIG. 3.

Many forms of dispensing machines, with various forms of stirrers and the like, were tried without success 20 until it was found that this inclined arrangement would give satisfactory operation. Indeed, it has been found that the angle itself is critical. Best results are achieved when the angle of inclination of the plane of the dispenser bottom relative to a horizontal plane is about thirty degrees (30°) but reasonably good results are obtained with departures of about ten degrees (10°) from this optimum inclination, that is, from about twenty degrees (20°) to about forty degrees (40°).

A rotating dispensing plate 28 is mounted on a shaft 29 passing at right angles through the center of the bottom so as to be located parallel to and very near the bottom and to rotate above the bottom, the plate having a plurality of dispensing openings 30, here, two, which have a truncated sector shape of about the same size as the discharge opening 23, as shown in FIG. 3, and which move past, or into and out of registry with, the discharge opening 23 in the bottom of the container as the plate 28 rotates. The plate 28 is spaced by a working clearance, say about $\frac{1}{16}$ ", above the bottom of the container.

45 The shaft 29 is driven by a motor M through a gear train unit 31. The shaft turns rather slowly and, as an example, may deliver a total batch of eight to ten unit charges at the beginning of each batch cleaning cycle.

As an example of dimensions which have been found 50 to be satisfactory in operation, the container is about 6" in diameter and about 12" high, the dispenser plate about 5 $\frac{1}{2}$ " diameter, and the openings about 1 $\frac{1}{2}$ " in radial length, 2 $\frac{1}{4}$ " outer width and about 1" inner width.

Another important aspect of successful operation for 55 delivering accurate charges at all stages of filling of the dispensing container is that one or more stirring rods 32 are carried by the rotating plate 28 behind one or more openings. As shown here, the rod is located near the outer periphery of the dispensing plate, where it will sweep material from the side wall of the container.

60 While stirring rods alone have been used with other dispensers, they have been found to give special advantages when used in combination with other elements herein provided. They are especially helpful in securing the delivery of uniform amounts of material for different stages of filling of the container between completely full and almost empty.

Also an important aspect is the provision of narrow 65 turned-up flanges 33 at the radially transverse trailing edges of the openings, reference being made to the direction of rotation of the dispensing plate as shown by the arrow in FIG. 3. The direction shown here is

clockwise. In one form which has operated well, the flange is about $\frac{1}{4}$ " to $\frac{5}{16}$ " wide and about $1\frac{1}{2}$ " long. The rod 32 may be attached to one of the flanges 33 as shown on the drawing.

The dispenser plate has a relatively large central raised core or enlargement 34 where it is secured to the shaft 29. Here the core is about $\frac{3}{4}$ " high and about 2" in diameter.

The container has a top or lid 35 fitting over the top end of the barrel, the lid being provided with a handle 36; and on the sides of the barrel the container is provided with hinged spring clips 37 which hold the lid on the container.

A timer 43, which may be of a conventional, well-known type, controls the operation of the dry cleaner in accordance with the desired cycle of operation. It includes a pair of contacts controlling the supply of current to the motor M, which contacts are closed during each automatic cycle of operation for a period of time providing the desired number of unit charges of powder. However, the present invention provides means for assuring that the dispenser plate 28 will be stopped in a position where neither of its openings 30 will register at all with the bottom discharge opening 23 of the container. As shown in FIGS. 2, 3 and 5, the shaft 29 is provided with a cam 40 having lobes 41 and, as shown in FIG. 5, a switch 42 of the leaf spring type has one blade located in a position where it is operated by the cam lobes as the shaft rotates. The lobes 41 are angularly located on the shaft 29 so as to close the switch as long as either opening 30 is in partial or complete registry with the discharge opening 23. Each lobe 41 has an angular extent which is approximately twice the angular extent of one of the mentioned openings, in order to close the switch during both the movement into registry and the movement out of registry. The switch 42 is connected in parallel or shunt with the contacts in the timer 43 that control the dispenser motor M. Thus, should the timer contacts happen to open during the time that one of the openings 30 is in complete or partial registry with the discharge opening 23, the switch 42 will maintain the circuit closed and energize the motor to rotate the plate 28 until the openings are out of registry, whereupon the switch 42 will open and permit the plate 28 to stop. This assures that the dispenser plate will not be stopped with either of the openings 30 of the plate in registry with the opening 23 of the container.

In operation, the dispensing container is filled with powder by an attendant as often as is necessary, say, once a day or once for each change or addition of cleaning fluid. At that time an initial batch of powder is put into the tub in addition to that used to fill the dispensing container. Thereafter, each time a batch of goods is put into the machine and the timing mechanism started, the dispenser will be operated for a predetermined length of time to introduce the desired number of measured charges into the tub and will then stop, the point of stopping being in a position where the plate openings 30 are out of registry with the bottom opening 23, as noted above.

When the motor turns the shaft 29, the dispensing plate 28 will be rotated in the direction indicated by the arrow in FIG. 3, as stated above. When a dispensing

opening 30 of the plate is in registry with the discharge opening 23, a charge of powder will drop out, but since the material has a bridging tendency it will form an arch over the opening. The edge flange 33 and the rod 32 break down this arch as they move forward and leave the powder in a continuous body above the dispensing plate ready for the next dispensing action. The rod 32 is especially useful in keeping the dispensing action uniform in various stages of filling of the container.

Due to the inclination of the dispenser bottom and the dispensing plate, the amount of powder dispensed each time will be substantially the same. The raised leading edge flanges of the solid plate material behind each dispensing opening and the stirring rod (or rods) 32 aid in this action, particularly in regard to different degrees of filling of the container. If the powder starts to bridge, the inclined arrangement will tend to cause it to break up and slide down over the rotating dispensing plate to the discharge opening, the stirrer 32 and the raised flange of the dispensing plate aiding in loosening material so it will flow down and fill the voids.

It is thus seen that the invention provides a simple, inexpensive, accurate, and dependable dispenser for powdered materials which have a bridging tendency.

While one embodiment of the invention has been described for purposes of illustration, it is to be understood that there may be various embodiments and modifications within the general scope of the invention.

What is claimed is:

A powder dispensing device comprising in combination, a powder container provided with a bottom having a discharge opening therein, a dispensing plate mounted for rotation above said bottom and having a dispensing opening located in a position to move into and out of registry with said discharge opening, a motor connected to said plate for rotating said plate, an electrical circuit connected to said motor for conducting electrical energy to said motor, a timer in said circuit in series with said motor for energizing said motor for a predetermined period of time, and means for maintaining energization of said motor while a dispensing opening is disposed in complete or partial registry with said discharge opening, said last-mentioned means comprising means shunting said timer, a switch in said shunting means adapted to effect energization of said motor independently of said timer, and a cam lobe movable with said dispensing plate and formed to move said switch to motor energizing position during that portion of the movement of the dispensing plate in which its dispensing opening is in partial or complete registry with said discharge opening.
